L. M. Rose, ATTORNEY.

UNITED STATES PATENT OFFICE.

WILLIAM STANTON LOCKE, OF CINCINNATI, OHIO.

VAGINAL SYRINGE.

SPECIFICATION forming part of Letters Patent No. 756,252, dated April 5, 1904.

Application filed April 4, 1903. Serial No. 151,047. (No model.)

To all whom it may concern:

Be it known that I, WILLIAM STANTON LOCKE, a citizen of the United States, residing at Cincinnati, in the county of Hamilton and State of Ohio, (whose post-office address is Groton Building, Seventh and Race streets, Cincinnati, Ohio,) have invented new and useful Improvements in Vaginal Syringes, of which the following is a specification:

10 My invention relates to "vaginal" syringe apparatus, its object being to provide an apparatus for the treatment of the vagina in diseased conditions or to prevent disease and relieve suffering by cleansing the surfaces of deleterious matter. The structures generally employed for this purpose fall short in various particulars of accomplishing the results most desired by competent physicians and in some cases injure the delicate organs they are 15 intended to benefit. In other cases their use is attended with inconvenience for want of suitable provision for drainage, &c.

My improvements are intended to provide an apparatus to accomplish the desired results in the most efficient manner and at the same time to remedy the evils and inconveniences referred to.

To this end it consists, first, in a novel construction of a discharge-nozzle combining in 30 its structure a distending apparatus whereby the entire wall of the vagina is exposed to the action of the discharged liquid; secondly, in a novel construction and arrangement of the discharge-conduits and appliances so as to 35 avoid injury to the uterus and at the same time direct the discharge in such manner as to facilitate the general movement of the discharged liquid outward to secure the general outflow and complete removal of deleterious 40 matter; thirdly, in the combination, with the discharge-nozzle, of a suitably-formed base to fit the body and prevent escape of liquid elsewhere than through the drainage-outlet provided therefor; fourthly, in the combination, 45 with the apparatus, of an air-valve to facilitate the escape of air and prevent injurious air-pressure in the use of the apparatus.

My invention is illustrated in the accompanying drawings, in which—

Figure 1 is an elevation of my device in 50 simplest form, showing a double-acting syringe attached; Fig. 2, an elevation of a slightly-modified structure; Fig. 3, a plan view of the cylindrical base and its cup-shaped flange.

Referring now to the drawings, and more 55 especially to Fig. 1, exhibiting my invention in its simplest form, A designates a short cylinder (or oval structure) constituting the base and support of a plurality of wires a, bent to form a structure A', conforming to the general contour of a vagina of the human body. At or near its lower end the cylinder A is provided with an oval cup-shaped flange B, adapted to fit the body exteriorly when the apparatus is in use. The cylinder A is closed at 60 the bottom, and projecting through and below said bottom is a pipe c, that extends through the cylinder and projects above the same as a discharge-nozzle axially within the wire structure A', terminating near its apex. At the 65 said apex of the wire structure A' is secured a small disk or "spreader" C' (preferably convex) in the projected axis of the nozzle C. The upper end of the cylinder A is provided with a perforated plate c', preferably a mere 70 "spider," as shown, to stay and support the wires and nozzle more firmly in relation to the cylinder. An outlet-tube d is also provided, opening through the bottom of the 75 cylinder A.

The mode of operation is as follows: The apparatus being applied as its nature indicates, the wire structure A' serves to hold apart the walls of the cavity, the muscles of which close upon and around the cylinder A, 80 preventing escape of fluid exteriorly around the same, while the lower ends of the tubes c d are connected by tubes t' t'', respectively, to an injecting device and to an exhausting device or place of discharge. Fluid injected 85 through the nozzle C is deflected radially outward by the spreader C, thus avoiding any direct stream against the uterus, yet bringing the entire body of the discharge to the ex- 90

treme inner end of the vaginal cavity, whence its flow is outward through the drainage-tubes d' d'' , cleansing the entire cavity and carrying any deleterious matter. The flange 5 B, fitting close to the body exteriorly, not only aids in preventing escape of fluids otherwise than through the appointed channel d , but also acts as a limiting-stop to secure the proper position of the apparatus in use and 10 preventing accidental injuries from careless or improper use.

An air-valve e is provided to permit free escape of air as desired in the use of the apparatus, thus preventing injuries to the delicate 15 membranes by air-distentions in the first injection of fluid.

The proper usefulness of the apparatus is enhanced by the employment of a syringe device combining the functions of injection and 20 exhaustion. A novel form of such a device is shown as part of Fig. 1, consisting of a double-acting cylinder syringe F, provided with finger-holds g , its piston-rod P, provided with a hand-rest r and surrounded by a coiled 25 spring S, impelling the piston normally upward when relieved of hand-pressure. Suitable valve connections f'' f'' are provided at the upper end, for example, of the cylinder F for attachment of the tube t' and a final discharge-tube t'' , while corresponding valve-connections f' f'' are provided at the lower end of the cylinder F for the injecting-tube t' and an inlet-tube t'' . The operation of this feature of 30 the apparatus is sufficiently indicated, the action at one side of the piston being to draw off and exhaust from the vaginal cavity coincidentally with the injecting action at the other side.

In the modification illustrated in Fig. 2 the 40 wires a are made tubular and connected below with the injecting-tube c and are provided at their inner sides with minute orifices (indicated by the arrows showing the direction of the discharge therefrom) to discharge directly 45 across against the walls of the vaginal cavity to assist the cleansing action. In all other respects the construction and the action are the same as previously described.

Peculiar advantages of the apparatus will be 50 obvious to the physicians and others familiar with the subject in the following particulars: The cylindrical base of the wire structure around which the vaginal muscles contract insures cleanliness as to the surroundings. The 55 cup-shaped flange attached to the cylindrical base not only aids the function of cleanliness in the use of the apparatus, but serves as a guide and limiting stop in placing the apparatus in proper position. The discharge-nozzle being carried within the wire structure to 60 near the inner end of the vaginal cavity insures a distinct and effective outward current

of fluid for cleansing purposes. The spreader, in connection with the discharge-nozzle, aids the cleansing action, at the same time protecting the uterus from injury. The air-valve affords means by which to relieve the painful distention of air-pressure. The construction of the apparatus facilitates sterilization by 65 boiling without injury to the device. The 70 combination with the apparatus of a novel and convenient syringe combines the functions of injections and exhaust.

The syringe apparatus being susceptible of other and independent uses is not claimed 75 herein except in combination, but is the subject of a separate application about to be filed.

I claim as my invention and desire to secure by Letters Patent of the United States—

1. An apparatus for vaginal treatment, embodying a suitably-formed base, perforated for the injection and exhaustion of fluids through the same, in combination with an open cage-like distending structure conforming in general contour to the forms and dimensions of the vaginal cavity, a discharge-tube within said structure and a cup-shaped deflector within the cage in the projected axis of the nozzle for diverting the course of the fluid and converting said fluid into spray. 90

2. In an apparatus for vaginal treatment the combination of a suitably-formed base, a wire distending structure concentric with the projected axis of the base and conforming substantially in general contour to the forms and 95 dimensions of the vaginal cavity, a discharge-nozzle positioned centrally in the cage and extending from the base thereof to a point near the apex, and a deflector attached to the cage in the projected axis of the nozzle for diverting the projected stream of fluid and converting it into spray. 100

3. In an apparatus for vaginal treatment the combination of a suitably-formed base, the injection and discharge tubes, and a cup-shaped 105 deflector disposed in the projected axis of the discharge-tube for diverting the course of the fluid-discharge and converting said fluid into spray.

4. In an apparatus for vaginal treatment, a 110 combination of a cylindrical base, a wire distending structure, carried by and concentric with the projected axis of the cylinder, a discharge-nozzle carried through said cylinder and terminating near the apex of the distending structure, a deflector or spreader attached to the wire structure in the projected axis of the nozzle, a spring-seated air-valve upon the cylindrical base and a discharge-tube leading 115 from said base, substantially as and for the purpose set forth. 120

5. In an apparatus for vaginal treatment a combination of a cylindrical base, a wire distending structure, carried by and concentric

with the projected axis of the cylinder, a discharge-nozzle carried through said cylinder and terminating near the apex of the distending structure, a deflector or spreader attached to the wire structure in the projected axis of the nozzle, and a discharge-tube leading from said base, substantially as and for the purpose set forth.

In testimony whereof I have hereunto set my hand in presence of two subscribing witnesses.

WILLIAM STANTON LOCKE.
